GARMENT HANGER FRAME

Filed July 2, 1929

George Subick INVENTOR
BY Victor J. Evans HIS ATTORNEY.

UNITED STATES PATENT OFFICE

GEORGE SUBICK, OF CHICAGO, ILLINOIS

GARMENT-HANGER FRAME

Application filed July 2, 1929. Serial No. 375,531.

This invention relates to certain novel improvements in garment hanger frames and has for its principal object the provision of an improved construction of this character which will be highly efficient in use and economical in manufacture.

It is among the objects of my invention to provide a device of the above named character which will be arranged so as to embody 10 two side members which are preferably of a one piece construction and which will preferably have portions thereof joined together by welding.

Another object of the invention is to provide 15 an expeditious arrangement for joining the side frames.

A still further object of the invention is to provide a frame which will embody portions that will support a protecting covering and 20 other portions on which garment hangers of approved form may be arranged.

A still further object of the invention is to provide a construction of the above described 25 character which in a modified form will embody spaced apart supporting members which will be adjustably connected to the side frames in order that they may be spaced apart in predetermined amounts.

Other objects will appear hereinafter. 30 The invention consists in the novel combination and arrangement of parts to be hereinafter described and claimed.

The invention will be best understood by reference to the accompanying drawings, 35 showing the preferred form of construction and in which:

Fig. 1 is a front elevational view of a preferred form of construction with which my invention is intended to be associated;

Fig. 2 is a top plan view of my improved 40 frame construction;

Fig. 3 is an end elevational view thereof;

Fig. 4 is a side elevational view of a modified 45 form of construction;

Fig. 5 is a plan view of the parts illustrated in Fig. 4;

Fig. 6 is a view looking in the opposite direction from Fig. 4; and

Fig. 7 is a sectional view taken substantially 50 on the line 7—7 in Fig. 3.

In the accompanying drawing wherein I have illustrated a preferred form of construction for my invention 10 and 11 indicate vertically extending supporting standards which are connected at their upper ends to a 55 cross member 12. The supporting standards 10 and 11 include foot portions 13 which serve to support the standards 10 and 11 to prevent displacement thereof. My improved frame is intended to be supported from the 60 cross member 12.

My improved frame is generically indicated by 14 and includes side members 15 and 16. By referring to Fig. 3 it may be seen that the side frame 16 includes an upper rail 65 17. One end of the upper rail 17 terminates in a looped portion 18 which looped portion 18 terminates in a downwardly extending portion 19. The portion 19 extends at an acute angle with respect to the extent of the 70 portion 17. The other end of the portion 17 terminates in a looped portion 20 which looped portion 20 in turn terminates in a portion 21 which extends downwardly at an acute angle with respect to the portion 17. 75 The portions 19 and 21 are connected to the lower end of a center brace member 22 which is also connected to substantially the midpoint of the extent of the portion 17. These various portions may be defined by stamping 80 the side frame 16 from a single piece of material or the side frame 16 may be formed from suitably shaped sections which will have the ends thereof suitably joined together as by welding.

Secured to the section 17 and extending upwardly therefrom in alignment with the center brace 22 is a hook 23. The side frame 15 is constructed in a manner substantially similar to that set forth.

By referring to Fig. 3 it may be seen that the center brace is arranged to extend vertically and the hook 23 is associated therewith so as to facilitate this. The section 17 is arranged to extend angularly with respect to 95 the horizontal and is preferably arranged so that the end embodying the loop portion 18 is arranged at a lower horizontal level than the end embodying the looped portion 20. The portion 15 is similarly arranged and the 100

utility of this arrangement will be set forth presently.

In order to join the side frames 15 and 16 together I provide rod members 24, 25, and 26. In the ends of the rod member 24 are tapped openings and bolt members 27 are extended through the looped portions 20 of the frames 15 and 16 and are threaded into these tapped openings. In a similar manner bolt members 28 are threaded into the ends of the rods 26 and the bolt members 28 are extended through the looped portions 18. Openings are provided in the center braces 22 through which bolt members 29 are extended which are also extended into tapped openings in the end of the cross brace 25. This extension of the bolt members into tapped openings in the ends of the rod members serves to very effectively join the side frames 15 and 16 together. If desired the rod members 24 and 25 and 26 may be made from tubular material which will facilitate the tapping of the openings in the ends thereof.

A supporting bar 30 extends between the center braces 22 adjacent the lower ends thereof and if desired this supporting bar 30 may be made from tubular material. The supporting bar 30 is arranged to embody tapped openings 52 in the ends thereof and bolt members 31 are extended through openings in the center braces 22 and are threaded into these tapped openings 52 and thus the supporting bar 30 is very effectively supported.

After the side frame 15 and 16 have been joined together in the manner set forth the hooks 23 are disposed on the horizontal supporting bar 12 and it is, therefore, manifest that the frame 14 will be supported from this bar 12. Prior to the time the hooks 23 are associated with the supporting bar 12 I arrange the sack 32 on the supporting frame 14. This sack 32 is preferably made from a suitable dust-proof textile material and has a slit in one face thereof indicated by 33 which may be opened in order that clothing or the like supported on suitable hangers may be inserted into this sack 32 and the hangers having the clothing associated therewith will be suspended from the bar 30. The particular arrangement of the textile sack 32 and the manner in which the clothing is associated therewith is particularly described and claimed in my co-pending application for Letters Patent of the United States, Ser. No. 358,360, filed April 26, 1929, which application relates to improvements in storage chambers.

In Figs. 4, 5, and 6 I have depicted a modified form of construction. Herein side frames are provided which include side plates 34. Secured to the ends of the side plates 34 are upwardly extending angle members 35 and these angle members 35 are secured to the side plates 34 in any approved

manner as by the rivets 36. An angle member 37 is connected to the upper ends of the uprights 35 in any approved manner as by welding and is connected to a similar angular member at the opposite end of the device and the angle member 37 corresponds to the member 17. Two such side frames are provided which are joined in a manner substantially similar to that hereinbefore set forth, that is hollow rod members such as 38 have tapped openings in the ends thereof into which bolt members 39 are extended which bolt members 39 are also extended through suitable openings in the frame. A supporting bar similar to the supporting bar 30 is also provided in the just described device but in addition to the supporting bar 30 I provide a supporting bar 40. Two such supporting bars 40 are provided in the device which are spaced apart in a predetermined amount and these supporting bars 40 are preferably arranged so as to be adjustable with respect to the distance therebetween and this is brought about in the following manner.

A plate 41 is provided which has a slot 42 formed therein. Headed rivets 43 are secured to the side plate 34 and are extended through the slot 42 and the heads on these rivets serve to hold and guide the plate 41 for rectilinear movement relative to the plate 34. A slot 44 is provided in the plate 34 and a bolt member 45 is extended through this slot and through an opening 46 in the plate 51 and the bolt member 45 is extended into the tapped opening in the corresponding end of the bolt member 40 and it is, therefore, manifest that the bolt member 40 will be effectively joined to the plate 41 and by tightening the screw 45 the plate 41 and the supporting bar 40 may be locked in predetermined positions. In order to properly adjust the bar 40 and maintain the same in transverse alignment with the bars 38 and the other bars in the frame I provide the following arrangement. In the plate 41 I provide a plurality of spaced apart holes 47. On the side frame 34 I provide a spring clip 48 which includes a right-angularly extending portion 49 that is extended through an opening 50 in the plate 34 and into a predetermined one of the openings 47. It is, therefore, manifest that the plate 41 may be moved into predetermined positions dependent upon the disposition of the portion 49 in the openings 47 and it is, therefore, manifest that the various plates 41 on the device may be correspondingly adjustable so as to bring about proper alignment of the supporting bars 40.

While I have illustrated and described the preferred form of construction for carrying my invention into effect, this is capable of variation and modification, without departing from the spirit of the invention. I, there-

fore, do not wish to be limited to the precise details of construction set forth, but desire to avail myself of such variations and modifications as come within the scope of the 5 appended claims.

Having thus described my invention what I claim as new and desire to protect by Letters Patent is:

1. In a frame of the character stated, side 10 plates, means for interconnecting said side plates, said side plates having slots formed therein, slide plates connected to said side plates adjacent said slots, bars extending between said slide plates, means extended 15 through said slots and into the ends of said bars for connecting said bars to said slide plates, and means for securing said slide plates in predetermined positions.
2. In a frame of the character stated, side 20 plates, means for interconnecting said side plates, said side plates having slots formed therein, slide plates connected to said side plates adjacent said slots, bars extending between said slide plates, means extended 25 through said slots and into the ends of said bars for connecting said bars to said slide plates, and means for securing said slide plates in predetermined positions, said last named means including resilient members 30 mounted on said side plates and including portions extending through said side plates into certain of a plurality of aligned openings provided in said slide plates.

In testimony whereof I affix my signature.

35 GEORGE SUBICK.
